ATTY.

UNITED STATES PATENT OFFICE.

JAMES M. BAKER, OF PROVIDENCE, RHODE ISLAND.

SHUT-OFF NOZZLE FOR FIREMEN'S HOSE.

SPECIFICATION forming part of Letters Patent No. 680,016, dated August 6, 1901.

Application filed February 26, 1901. Serial No. 48,993. (No model.)

To all whom it may concern:

Be it known that I, JAMES M. BAKER, a citizen of the United States, residing at Providence, in the State of Rhode Island, have invented a new and useful Improvement in Shut-Off Nozzles for Firemen's Hose, of which the following is a specification.

My invention relates to an improved shut-off nozzle, which is easily operated throughout the whole extent of its movement; and it consists in the improved combination and arrangement of parts, as hereinafter set forth and claimed.

In the accompanying drawings, Figure 1 represents a side view of a shut-off nozzle embodying my improvement. Fig. 2 represents a longitudinal section taken in the line 2 2 of Fig. 1, showing the opened condition of the shut-off valve. Fig. 3 represents a partial section showing the shut-off valve in its closed condition. Fig. 4 represents a transverse section taken in the line 4 4 of Fig. 2, showing a plan view of the valve-seat.

In the drawings, A represents the play-pipe, to which the shut-off nozzle B is secured by means of the screw-thread c. The annular valve-seat a is formed concentric with the circular wall of the shell b and connected thereto by means of the connecting-bars k k, the said shell being preferably formed with a spherical enlargement d and with a cylindrical portion d', provided at its upper end with the opposite slots e e, which are open at their outer ends, adapted to receive the studs f f, formed upon the valve-tube g, and outside the cylindrical portion d' of the shell b and preferably with an intervening space d' is placed the outer tube h, which is firmly secured to the shell b by means of the screw-thread i, the upper end of the said outer tube h being provided with the internal annular shoulder h', and within the outer tube h is placed the nozzle-tube j, provided with the annular shoulder h'' and the packing-ring h'', by means of which the nozzle-tube j is prevented from being forced outward from the outer tube h, and the loose joint j' between the tubes h and j is made water-tight. The nozzle-tube j is held loosely within the outer tube h, the inner end of the said tube j resting against the outer end of the cylindrical portion d' of the shell b, and the said nozzle-tube j is provided with the internal screw-

thread j'', which engages with the external screw-thread j''' of the valve-tube g, and also provided with the fluted outer surface m, by means of which the said tube j may be conveniently rotated by hand to cause the opening or closing of the valve n, the said valve being shown in its opened condition in Fig. 2 and in its closed condition in Fig. 3, the valve-tube g being held from rotation with the rotation of the nozzle-tube j by means of the studs f f, which are adapted to move back and forth in the slots e e. The nozzle-tube j is provided at its outer end with the removable tip o and with the bushings o' o'' for throwing streams of different sizes. The valve-tube g is provided with the packing-ring g', and on account of its nearly-balanced condition is easily operated for opening and closing the valve by means of the screw-threads j'' and j'''.

I claim as my invention—

1. In a shut-off nozzle, the combination of the revoluble nozzle-tube, with the sliding valve-tube actuated by the revolution of the nozzle-tube, and the closing seat for the valve-tube, substantially as described.

2. In a shut-off nozzle, the combination of the shell provided with the spherical enlargement the cylindrical portion provided with a guiding-slot open at its outer end and the centrally-arranged valve-seat, with the valve-tube provided with a stud held in the slot of the shell, and serving to prevent the rotation of the valve-tube, substantially as described.

3. In a shut-off nozzle, the combination of the shell provided with the cylindrical portion having a guiding-slot open at its end and the centrally-arranged valve-seat, with the valve-tube provided with a stud held in the guiding-slot of the shell, and with the external screw-thread formed upon the outer end of the valve-tube beyond the end of the slot in the shell, the revoluble nozzle-tube provided with the internal screw-thread engaging with the external screw-thread of the valve-tube, and means for holding the said valve-tube and the nozzle-tube in proper working relation with each other, substantially as described.

JAMES M. BAKER.
